[57] CLAIM

An ornamental design for a remote control accessory, as shown and described.

DESCRIPTION

FIG. 1 is a reduced perspective view of a remote control accessory, showing my new design, the broken lines showing a remote control being for illustrative purposes only, and forms no part of the claimed design.

FIG. 2 is a bottom plan view thereof;

FIG. 3 is a top plan view thereof;

FIG. 4 is a side elevation view thereof;

FIG. 5 is a front elevation view thereof; and,

FIG. 6 is a rear elevation view thereof.
